(57) CLAIM

I claim the ornamental design for a shopping cart, as shown and described.

DESCRIPTION

FIG. 1 illustrates a perspective view of a shopping cart showing my new design;

FIG. 2 illustrates a front view of a shopping cart showing my new design;

FIG. 3 illustrates a back view of a shopping cart showing my new design;

FIG. 4 illustrates a right side view of a shopping cart showing my new design;

FIG. 5 illustrates a left side view of a shopping cart showing my new design;

FIG. 6 illustrates a top view of a shopping cart showing my new design; and,

FIG. 7 illustrates a bottom view of a shopping cart showing my new design.

The broken lines of FIGS. 1–7 are for illustrative purposes only and form no part of the claimed design.
